DESIGN FOR A SHOE OR SIMILAR ARTICLE

Lorenzo Audino, East Elmhurst, N. Y.

Application April 10, 1935, Serial No. 56,307

Term of patent 3½ years

To all whom it may concern:

Be it known that I, Lorenzo Audino, a citizen of the United States, residing in East Elmhurst, in the county of Queens and State of New York, have invented a new, original, and ornamental Design for a Shoe or Similar Article, of which the following is a specification, reference being had to the accompanying drawing, forming part thereof.

I claim:

The ornamental design for a shoe or similar article, as shown.

LORENZO AUDINO.
